(57) **CLAIM**

The ornamental design for a baseball glove, as shown and described.

DESCRIPTION

FIG. 1 is a front perspective view of the baseball glove of the present invention;

FIG. 2 is a side view of the baseball glove of FIG. 1 showing the thumb side of the glove;

FIG. 3 is a back perspective view of the baseball glove of FIG. 1;

FIG. 4 is another back perspective view of the baseball glove of FIG. 1;

FIG. 5 is a top perspective view of the baseball glove of FIG. 1; and,

FIG. 6 is a bottom perspective view of the baseball glove of FIG. 1.

The broken lines are for illustrative purposes and form no part of the design.
